WARE SUPPORT

Filed Feb. 21, 1930

INVENTOR.
ROGER W. ROWLAND
BY *J. E. Hubbell*
ATTORNEY

UNITED STATES PATENT OFFICE

ROGER W. ROWLAND, OF NEW CASTLE, PENNSYLVANIA, ASSIGNOR TO NEW CASTLE REFRactories COMPANY, OF NEW CASTLE, PENNSYLVANIA, A CORPORATION OF DELAWARE

WARE SUPPORT

Application filed February 21, 1930. Serial No. 430,178.

The present invention relates to supports for ware pieces and particularly flat or shallow ceramic ware and tile pieces, during a kiln firing operation and the handling operations incidental to the firing operation.

The general object of my present invention is to provide an improved device for supporting ware which is characterized by its simplicity and low cost of construction, 10 ease of handling in the loading and unloading operations, strength, and adaptability for use in various kiln processes and under varying conditions of use.

A further object of my invention is to 15 provide an improved method of manufacturing a ware support embodying my improved construction.

The various features of novelty which 20 characterize my invention are pointed out with particularity in the claims annexed to and forming a part of this specification. For a better understanding of the invention, however, and the advantages possessed by it, reference should be had to the accompanying drawings and descriptive matter 25 in which I have illustrated and described preferred embodiments of the invention.

Of the drawings:—

Fig. 1 is an end view of a kiln car for a 30 continuous tunnel kiln provided with a preferred arrangement of the ware supports;

Fig. 2 is an end view of one of the ware supports illustrated in Fig. 1;

Fig. 3 is a side view of the support shown 35 in Fig. 2; and

Fig. 4 is a perspective of a modified form of support.

In the drawings, I have illustrated several forms of my improved support as utilized 40 for supporting pieces to be heat treated such as shallow ware pieces, flat slabs or tiles, on a kiln car of a continuous tunnel kiln. When such supports are used for carrying a multiplicity of tile pieces, they are commonly known in the art 45 as "tile setters". In general, my improved ware support consists of a main supporting member of substantially the same form as certain standard structural steel shapes 50 which include a horizontal base supporting

flange and a web secured thereto and projecting vertically therefrom. The web is provided with a plurality of laterally projecting parts, and as pins or shelves, on which the pieces are mounted. Various 55 standard structural steel shapes are adapted for such use, such as I-beams, channel, T and Z bars, and H-columns, the particular shape utilized in the kiln being dependent primarily on the operating conditions 60 present.

As illustrated in Figs. 1 to 3 of the drawings, one preferred form of support constructed in accordance with my invention comprises an elongated main supporting member A of a substantially standard I-beam form having a horizontal base flange member A', a central web A² extending vertically from the middle of the base flange A' to the middle of a horizontal top flange member A³, the parts being preferably made in a one-piece integral form by casting or rolling. The supporting member may be made of refractory material or a heat resistant metallic alloy. 75

The central web A² is provided with a plurality of horizontal and vertical rows of openings A⁴ shaped in accordance with the cross-sectional form of rods or pins B which are adapted to be inserted in corresponding 80 openings A⁴. The pin cross-sections and openings are preferably in the form of an equi-lateral triangle arranged with its lower side horizontal. Each pin is preferably arranged in the corresponding opening with its opposite ends equi-distant from the corresponding side of the web A² and extending horizontally to points between said web and the vertical planes including the upper flange side edges. When the pins are so 85 arranged, the pieces to be supported, such as the tiles C shown, are positioned on the pins, each tile being supported in a horizontal position on two or more adjacent pins, as shown in Figs. 1 and 3. The loaded 90 supports are then placed on a kiln car, preferably as hereinafter described, if the heating furnace is a continuous tunnel kiln. 95

It will be readily understood that the proportioning of the supporting parts can be 100

varied in accordance with the size of the pieces to be fired and the operating conditions present. I have for example, for firing 4½" square tile constructed a tile setter with approximately a depth of 14½", an upper and lower flange width of 9½", and a length of 18", the web containing twelve horizontal rows of pin openings vertically spaced 1½" between centers. The 10 pin openings and pins may be of various cross-sectional forms, a triangular or square form, however, being particularly advantageous due to the knife edge contact obtainable between the pins and ware pieces. The pins may be easily removed and renewed or replaced with another knife edge in the contacting position.

It will be noted that the main supporting member A is a unitary self-supporting member in stable equilibrium both when the support is loaded and unloaded and requires no auxiliary members to maintain it in position. The upper flange present in the I-beam type is advantageous in providing means for protecting the ware surfaces from sand or other débris dropping from above and in providing a supporting base for superposed supports and means by which the ware supports can be easily handled during the car loading and unloading operations. The weight of the supports is relatively small, permitting the supports to be loaded by female labor at work benches. The construction permits rapid loading and unloading operations, particularly with tile pieces, which can be quickly removed from the support by shaking.

The ware supports of my invention are especially adapted for various arrangements longitudinally or transversely of the kiln car. A preferred arrangement is illustrated in Fig. 1 by which the tiles normally in the portion of the car receiving under-heating receive the proper amount of heat, while the tiles in another portion normally exposed to excessive temperatures are partly protected. As shown in Fig. 1, a kiln car D, which is of a type well understood in the art, is loaded with a plurality of rows of ware supports LA with their webs extending transversely of the lower portion of the car with the adjacent supports in each row in substantially end to end contact and the adjacent supports in adjacent rows having their upper and lower flange edges substantially in contact. A second tier of supports LA may be positioned on the upper flanges of the lower row, as shown. This transverse arrangement of the supports in the lower portion of the car forms transverse channels for the circulating kiln atmosphere, thereby increasing the heat transfer to the tiles.

Mounted on the uppermost transverse 65 tier are one or more tiers of supports HA,

the supports HA in each tier being arranged longitudinally of the car with the adjacent supports in each row in end to end contact, thus diminishing the transverse circulation of the kiln atmosphere in that portion of the car and thereby reducing the usually excessive heating of the tiles therein.

In Fig. 4 I have illustrated a modified form of support having the described arrangement of upper and lower flange members A' and A³, respectively, and a central web A². In lieu of the web openings and supporting pins, I have provided a series of vertically spaced horizontally projecting shelves F, which extend longitudinally of and are integrally connected to the web A³.

The ware support of Fig. 4 is preferably manufactured by an extrusion process in which a supply of plastic refractory material is forced through a die of the proper shape by an extrusion machine to produce a one-piece rectangular tube having vertical side walls A⁵ as indicated by broken lines in Fig. 4, and a plurality of internal shelves 90 and a vertical web extending between and integrally connected to the tube walls. After a desired amount of material has been extruded, the vertical side walls A⁵ of the extruded article are cut away from the shelves and flanges, leaving a ware support of the form indicated in full lines in Fig. 4. The extruded article is subjected to the necessary firing operations and the support is then ready for use.

While in accordance with the provisions of the statutes, I have illustrated and described the best forms of embodiment of my invention now known to me, it will be apparent to those skilled in the art that changes may be made in the form of the device and of the method of manufacture disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. A support for ceramic ware comprising an elongated main supporting member having a base flange and a vertical web, and a plurality of horizontally extending ware supporting members extending laterally from said web.
2. A support for ceramic ware comprising an elongated main supporting member of a substantially standard structural shape including a horizontal base flange and a vertical web, and laterally projecting members carried by said web for supporting ware pieces.
3. A support for ceramic ware comprising

ing an elongated main supporting member having a substantially standard I-beam cross-section, and a plurality of ware supporting pins mounted in the web of said main supporting member and projecting horizontally at each side thereof.

4. A tile setter comprising an elongated main supporting member having horizontally extending top and bottom flanges and a central web extending vertically between and integrally formed with said flanges, a plurality of horizontal rows of openings formed in said web, and a pin mounted in each of said openings arranged to project a predetermined distance from each side of said web, whereby a plurality of tile pieces are adapted to be supported on said pins at each side of said web.

5. In a kiln car, a plurality of rows of ware supports, each having a vertical web arranged transversely of the lower portion of the car to form a series of transverse channels, and a plurality of rows of similar ware supports mounted on said first mentioned rows and each having its vertical web extending longitudinally of the car, whereby the transverse circulation of the kiln atmosphere is increased in the lower portion and decreased in the upper portion of the car.

6. A support for ceramic ware comprising an elongated main supporting member having a substantially standard I-beam cross-section, and a plurality of ware supporting shelf members integrally connected to the web of said main supporting member and projecting horizontally at each side thereof.

Signed at New Castle, in the county of Lawrence and State of Pennsylvania, this 13 day of February, A. D. 1930.

ROGER W. ROWLAND.
